UNITED STATES PATENT OFFICE.

JOSEPH D. WOODBURY, OF SPRINGFIELD, MASSACHUSETTS, ASSIGNOR OF
ONE-HALF TO ORRIN L. COWLES, OF SAME PLACE.

LATCH.

SPECIFICATION forming part of Letters Patent No. 593,182, dated November 2, 1897.

Application filed December 12, 1896. Serial No. 615,451. (No model.)

To all whom it may concern:

Be it known that I, JOSEPH D. WOODBURY, a citizen of the United States of America, residing at Springfield, in the county of Hampden and State of Massachusetts, have invented new and useful Improvements in Fastening Devices for Doors, of which the following is a specification.

This invention relates to locks and spring-latches for doors, &c., and has for its object the automatic alinement of the two parts of the lock located, respectively, on the door and the door-casing; and the invention consists in the construction and arrangement of the said two parts of the lock, all as herein-after set forth and claimed.

In the drawings forming part of this specification, Figure 1 is a view of a spring-latch case and its keeper embodying my invention applied to a door and casing. Fig. 2 is a section of Fig. 1 on line 22 of that figure. Fig. 3 is a side view of the latch-case separated from and out of line with the keeper. Fig. 4 is a top edge view of the latch and its keeper in a position of engagement. Fig. 5 is a perspective view of the back side of a spring-latch and its keeper.

All of the above views embody my invention.

Referring to the drawings, the only form of door-fastening shown is a spring-latch of the usual construction having my invention applied thereto, although the invention is equally applicable to almost any form of lock or spring-latch or bolt.

A represents a spring-latch case of ordinary construction and which has formed upon its inner end the two cam-surfaces *b* and the two stops *d*, which project beyond the inner end of the case any suitable distance, as shown in Figs. 1 and 5. The stops *d* project forward in a line with the base of the latch, but the two cam-surfaces *b* incline toward each other at any suitable angle from opposite edges of the frame and serve to catch over opposite edges of the keeper *B*. This keeper *B* is of ordinary construction and may either have inclined sides or sides which project at right angles from the base, but as here shown the sides *f* are made to incline toward each

other, so as to correspond to the angle of the cam-surfaces *b*. As shown in Fig. 5, no change whatever is made in the keeper *B*, and the only change that is made in the case *A* is in having the stops *d* and the cam-surfaces *b* project at its inner end, so as to catch over the keeper *B*. The angle at which the cam-surfaces *b* extend to the inner end *a* of the latch-casing is immaterial so long as these cam-surfaces catch over the keeper *B* for the purpose hereinafter described. An improved appearance is given the case by forming the stops *d* integral with said cam-surfaces, said stops being simply a continuation of the surface of the cams at a suitable angle thereto and also at right angles to the end *a* of the case and parallel to the front and rear surfaces thereof. These stops are in no way essential to the operation of the cam-surfaces, but they form efficient means for preventing the swinging of the door too far past the edge of the casing on the closing of said door, whereby the hinges might be strained or broken.

By the use of a latch or lock case of this construction all the weight of the door is taken off from the hinges when the door is closed. Furthermore, while the drawings show two inclined cam-surfaces one may suffice under certain circumstances.

The keeper *B* is shown in the drawings as having its sides *f* inclined to correspond to the inclination of the cam-surfaces *b*. While the coinciding angles of the parts *b* and *f* improve the appearance of the fastening, the said sides *f* of the keeper might be made at right angles to the front and rear faces of the case without interfering with the easy operation of the said cam-surfaces on the keeper.

From the above description it will be observed that if a door which has the herein-described cam-surfaces applied to the fastening devices thereof sags to such an extent that the bolt is out of line with the keeper or a latch out of line with its latch-plate in the casing said defect is remedied, and upon the closing of said door and the contact of said inclined cam-surfaces *b* with the keeper or other suitably-located fixed part the said bolt or latch is brought into proper operative position.

tion for engagement with the keeper, the perfect alinement of the bolt or latch and the part which receives it being automatically effected, whether the lock or spring-latch be 5 fastened to the door or to the door-casing.

It is obvious that it is only necessary for the efficient action of this construction that one or the other of the two parts of the lock—viz., the case or the keeper—be provided with 10 an inclined cam-surface for engagement with a portion of the other of said parts, whereby the two are brought into proper alinement.

No change is made in my fastening device for doors except the latch-case is provided 15 with inclined cam-surfaces upon its inner end, and which form extensions of the side edges of the casing, and the stops *d*, which form

extensions of the side flanges of the casing through which the screws are passed.

Having thus described my invention, what 20 I claim, and desire to secure by Letters Patent, is—

In a fastening device for doors, the latch-case, provided with cam-surfaces *b* which project over the inner end of the casing, and are 25 inclined inwardly toward each other, combined with a keeper, over the opposite edges of which the cam-surfaces catch when the door is closed and prevent the door from sagging, substantially as shown.

JOSEPH D. WOODBURY.
